(57) **CLAIM**

I claim the ornamental design for the multiple piece baseball batting training apparatus, as shown and described.

DESCRIPTION

FIG. 1 is a perspective view of my design for a multiple piece baseball batting training apparatus.

FIG. 2 is a front elevation thereof.

FIG. 3 is a side edge elevation thereof; and,

FIG. 4 is a front elevation thereof.

The broken lines on my multiple piece baseball batting training apparatus shown in FIGS. 1-4 are for illustrative purposes only and are not part of the claimed design.
